UNITED STATES PATENT OFFICE.

HERBERT SPARKS, OF HASTINGS, ENGLAND.

GAS LIGHTER OR EXTINGUISHER.

SPECIFICATION forming part of Letters Patent No. 747,014, dated December 15, 1903.

Application filed November 26, 1902. Serial No. 132,976. (No model.)

To all whom it may concern:

Be it known that I, HERBERT SPARKS, a subject of the King of Great Britain, and a resident of Stewart Lodge, Baldslow Road, 5 Hastings, in the county of Sussex, England, have invented certain new and useful Improvements in Gas Lighters or Extinguishers, of which the following is a specification.

This invention relates to certain new and 10 useful improvements in gas lighters and extinguishers; and the object of my invention is to provide a mechanical arrangement for raising and lowering a gas-flame at predetermined times.

15 With this object in view my invention consists in the device as will now be more particularly described in detail and then definitely claimed at the end hereof.

20 In the accompanying drawings, which represent the preferable embodiment of my invention, Figure 1 is a side elevation of a portion of a gas-burner with my attachment thereon. Fig. 2 is a perspective view, on a larger scale than Fig. 1, of the attachment 25 detached. Fig. 3 is a side elevation, also on a larger scale than Fig. 1, of the bottom of the box with the front removed to show the arrangement of the lever.

Referring now to the details of the drawings by letters, A designates a pivoted lever 30 shown on an enlarged scale in Fig. 2 and to which is secured two arms B B', each of said arms being used to carry over a weight alternately from one side to the other, as will be 35 hereinafter described.

Coacting with the arms B B' is a weight C, supported by an arm C', pivotally supported in any desirable manner, so that the arm C' is located between the two arms B and B', 40 heretofore described, as is clearly shown in Fig. 2.

Arranged, preferably, above the lever A and these arms B B' is a gas-burner preferably of the usual incandescent character, 45 which burner is provided with an ordinary or any form of tap or cock D. To one end of this tap or cock D is secured two arms E E', which project on opposite sides of the tap D.

50 The arrangement of the parts so far described is such that whenever the lever A is moved from one side to the other one of its

arms B or B' contacts with the arm C' and moves it. Just as soon as this arm passes the perpendicular its attached weight causes 55 it to fall over to the other side, thus striking on one of the arms E E', the continued movement of the weight causing the arm on which it falls to move, thus moving the tap or cock D and controlling the flow of gas. Thus in 60 Fig. 2 when the arm A is moved to the left its arm B' is caused to move against the arm C' and move said arm and its weight C toward the left and away from the arm E', projecting from the tap or cock D. Just as soon 65 as the arm C' is moved to the slightest extent past the perpendicular the weight C falls by gravity, strikes the arm E, and thus moves it and at the same time operates the tap or cock D. 70

Any preferred means may be used to operate the lever A; but I have shown in my drawings the form I now prefer, which consists of a disk F, operated by clockwork, shown in conventional form in dotted lines, 75 and to this disk is secured two pins G and G'. One of these pins, G, is arranged to travel so as to move against an arm a, projecting from the lever A, and thus move the lever toward the left looking at Fig. 3. After the lever 80 A has been moved by the pin G so that the lever is thrown over to the opposite position from that shown in Fig. 3 the other pin, G', moves around and against the arm a', projecting from the lever A, and thus moves 85 said lever back to the position shown in Fig. 3. Although I have described the means for operating this lever, it will be understood that my invention is not limited thereto, but any suitable means may be used for this purpose. 90

It will be obvious that changes and modifications may be made without departing from the lines of my invention as set forth in the following claims. 95

Having now particularly described my invention, what I claim as new is—

1. In apparatus of the character described, the combination of a gas-cock, a weight arranged in proximity thereto and pivoted independent thereof, the pivot of the weight being below its center of gravity, said cock having means coacting with said weight and movable thereby as the weight falls thereon, 100

and means for operating said weight to carry its center of gravity over the pivot, substantially as described.

2. In apparatus of the character described, 5 the combination of a weight pivoted below its center of gravity, a gas-cock having arms projecting on opposite sides thereof and in the path of said weight, said arms and their cock being movable as the weight falls on either

of said arms, and means for moving said weight to carry its center of gravity over its pivotal point, substantially as described.

Signed by me at Stewart Lodge aforesaid this 10th day of October, 1902.

HERBERT SPARKS.
